UNITED STATES PATENT OFFICE.

LEWIS K. BROWN, OF ASOTIN, WASHINGTON.

STEAM-DRIVEN COMBINED HARVESTING AND THRESHING MACHINE.

No. 901,588.

Specification of Letters Patent.

Patented Oct. 20, 1908.

Application filed March 2, 1907. Serial No. 360,215.

To all whom it may concern:

Be it known that I, LEWIS K. BROWN, a citizen of the United States, residing at Asotin, in the county of Asotin and State 5 of Washington, have invented new and useful Improvements in Steam-Driven Combined Harvesting and Threshing Machines, of which the following is a specification.

This invention relates to a steam driven 10 combined harvesting and threshing machine embodying in its general organization a reaping device and a threshing, separating and cleaning mechanism to which the material cut by the reaper is delivered by suitable conveyers which are continuously driven 15 during operation of the machine together with power engines carried on the machine for propelling the latter from the ground and for driving the reaping, conveying, 20 threshing, separating and cleaning mechanisms.

The invention has for its objects to provide a comparatively simple, inexpensive machine of this type whereby the grain will 25 be harvested during forward travel of the machine over the ground and delivered onto the conveyers, one wherein the latter will be properly and continuously driven for carrying the grain to the threshing mechanism, 30 one in which the operation of the various mechanisms may be controlled at will and this irrespective of the machine being at rest or in motion over the ground, and one which will travel in its own swath through a field 35 without treading down any of the standing grain.

A further object of the invention is to provide an improved light-weight portable mechanism for separating the grain from 40 the straw, and to reclean the grain after it passes the ordinary shoe and before it passes from the machine.

A further object of the invention is to provide a simplified propelling mechanism for 45 driving the machine in its travel over the ground, together with means for steering the machine and yieldably supporting the framework of the latter which in turn sustains the engines and attendant parts.

With these and other objects in view, the 50 invention comprises the novel features of construction and combination of parts more fully hereinafter described.

In the accompanying drawings: Figure 1 55 is a side elevation of a harvesting and threshing machine embodying the invention.

Fig. 2 is a top plan view of the same. Fig. 3 is a side elevation on an enlarged scale and partly in section of the threshing mechanism, showing the conveyers for returning the 60 material to be rethreshed and for discharging the threshed material from the machine. Fig. 4 is a section taken longitudinally, 65 through the threshing mechanism. Fig. 5 is a view on an enlarged scale and partly in section of the engines and their attendant parts. Fig. 6 is an enlarged side elevation, 70 partly in section, of a portion of the running gear, showing the manner of mounting and driving the rear transporting wheels. Fig. 7 is an elevation of the front and steering 75 wheels on an enlarged scale. Fig. 8 is a horizontal section taken on the line 8—8 of Fig. 7. Fig. 9 is a detail view of the compensating gear. Fig. 10 is a detail view of 80 a portion of the drive shaft, showing the automatic clutch. Fig. 11 is a view partly in longitudinal section of one of the conveyers for carrying the material from the reaping to the threshing mechanism. Fig. 12 is a similar view of the other of said 85 conveyers. Fig. 13 is a detail cross section taken on the line 13—13 of Fig. 12. Fig. 14 is a plan view on an enlarged scale of a portion of the sickle blade, together with its operating lever. Fig. 15 is a detail view, 90 partly in vertical cross section and on an enlarged scale, of the sickle bar and its attendant parts. Fig. 16 is a detail front elevation of the sickle blade as viewed in the direction of the arrow in Fig. 15, and shows the sickle drive in detail.

Referring to the drawings, it will be seen that the machine, the frame of which includes a horizontal table 1, is mounted for transportation on a running gear comprising a rear axle 2 equipped with transporting wheels 3 and a front axle 4 having pivoted end portions or sections 6 adapted to swing on a horizontal plane and on which are 95 keyed the front transporting wheels 5, having hubs set out, bringing the wheel bearings under the boxings 7 or sleeves, Fig. 7. These sleeves have upwardly and downwardly extending arms 7^a terminating in pivots 7^b that 100 turn in bearings 7^c on the housing 61, which latter carries the weight of the front end of the platform 1. To the sleeves, which swing on vertical axes by the pivots 7^b, are fixed inwardly and rearwardly projecting arms 8 105 having their forward ends connected for uniform movement by a link 9, and pivoted

to one of the arms is a rack bar 10, the teeth 11 of which are in mesh with a pinion 12 in turn fixed at the lower end of a vertical steering post 13. This post rotates in a bearing 12^d on the housing 61 and has fixed on its upper end a hand wheel 14 through the medium of which the post may be rotated, thereby serving through the pinion and rack connection to turn the axle sections 6 on the pivots 73 for guiding the machine in its travel over the ground.

Sustained at the forward end of the machine by means of two pairs of supporting members or bars 15 pivoted at their rear ends 15 as at 16 to the front of the platform, is a reaper frame 17 adapted to swing in a vertical plane toward and from the ground surface and to be normally supported in elevated condition through the supporting members or beams 18 pivoted to the platform 20 and provided at their forward ends with shoes or runners 19 which travel on the ground surface, there being fixed to the bars 18 vertically uprising standards 20 which 25 project upward through the guides 21 on the back of the frame 17. The upper ends of the standards 20 are toothed to form racks *a* and are connected together by means of a shaft *b* sustained at the top of the rear portion of 30 the platform 17, there being fixed on the ends of the shaft pinions *c*, meshing with the racks *a* and serving to maintain the outer ends of the frame 17 at equal distances from the ground, while the height of the sickle on 35 the balanced platform 17 is regulated by means of a bevel gear *d* fixed on the shaft *b* and engaged by a bevel pinion *e* carried by a shaft *f* arranged counter to the shaft *b* and extended rearward to the operator's platform 40 and provided at its rear end with a crank wheel *g* adapting the parts for convenient operation.

Journalized in bearings 22 in the frame 17 is a rotary reel shaft 23 carrying a rotary 45 feeding reel 24 which in practice directs the grain or other material to be cut inward between the fingers of a stationary sickle bar 25 sustained at the front of the reaper frame and coöperating with a reciprocatory sickle 50 blade 26 for reaping the grain in the usual manner, while pivoted intermediate its ends between a pair of vertical bearing standards 27 is a balance beam 28 provided at its rear end with a weight 29 and having its forward 55 end connected by a link 30 with the rear side of the reaper frame 17 for balancing the latter.

Extending longitudinally of the frame 17 is a pair of endless conveyer belts 31, 32, of 60 which the former travels upon rollers 33 and 34 journaled in the frame, while the belt 32 is arranged for travel on rollers 35 and 36, the belts 31 and 32, which are spaced apart at their inner ends, being so connected for 65 operation that their top portions travel to-

ward one another, while sustained at one side of the platform 1 and extending longitudinally thereof is a rearwardly and upwardly inclined conveyer belt 38 having its forward end positioned in the space between the 70 inner ends of the belts 31, 32, for receiving material therefrom, the rear end of the belt 38, which is arranged for travel over rollers 39 and 40, being disposed for delivering material through the opening 41 into the casing 75 42 of a threshing mechanism sustained at the rear of the platform 1. The portion of the forward end of the belt 38 which lies between the ends of belts 31 and 32 is held for travel in a horizontal plane by means of idler rollers 80 43, as seen more clearly in Figs. 12 and 13.

Arranged beneath the platform 1 is a water tank 44 designed to render the platform more rigid and to carry water for feeding a boiler 45 sustained on the platform and in 85 turn connected by means of a pipe 46 with an engine 47 and by a steam pipe 48 with a pair of engines 49, both of which are connected for driving a main power shaft 50 on which is fixed a pinion 51 in mesh with a 90 gear 52 fixed upon a second driving shaft 53 arranged vertically beneath and for operation from the shaft 50 on which there is also fixed a fly wheel 54, while fixed on the shaft 53 is a sprocket pinion 55, connected 95 by a chain 56 with a sprocket gear 57 arranged on the front axle 4 for driving the latter, there being also fixed on the shaft 53 a sprocket pinion 58 connected by a chain 59 with a sprocket gear 60 on the rear axle 100 2 for driving the same. It is to be observed in this connection that the gear 57 on the front axle is housed in a metal casing 61 which carries the front end of the platform 1 on its gudgeons 61' and that the rear axle 105 2 extends through a tubular casing 62 extended transversely through the tank 44 and serving to relieve said axle from contact with the water in the tank, and to form an adequate space in which the shaft operates, 110 while at the forward end of the tank is formed a housing for the counter shaft 53 and its attendant gearing and bearings, these parts being all fastened together in one piece, thus rendering the platform rigid. It 115 is to be observed in this connection that the platform 1 extends at its forward end over the housing 61 and that the tank 44 is formed beneath the rear portion of the platform, while various brackets, braces and 120 supplemental platforms for supporting the various parts of machinery and the men for operating the same are fastened on the above described structure.

The sprocket 57 is included in a compensating gear comprising a pair of bevel pinions 63 journaled in suitable bearing openings 64 in a sprocket and arranged to mesh with a pair of bevel gears 65, 66, arranged at 125 opposite sides of the sprocket gear and in 130

turn fixed respectively on the axle 4 and on a sleeve 67 arranged for rotation on the axle 4 and independently thereof, it being understood that the axle is connected for driving 5 one of the front wheels while the other of said wheels turns with the sleeve, this arrangement being for the usual purpose of permitting proper differential rotation of the wheels in the operations of turning and 10 guiding the machine.

Extended longitudinally of the reaper frame 17 and journaled in suitable bearings at the rear thereof is a shaft 68 geared by a chain 69, arranged on suitable sprockets, 15 with the reel shaft 23 for rotating the reel and also connected by a cross belt 70 with a shaft 71 from which the conveyer 38 is driven by means of a chain belt 72 leading to the shaft 73 of the roller 40, there being 20 fixed on the shaft 71 a bevel gear 74 in mesh with a pinion 75 fixed upon and for driving a countershaft 76 which is in turn connected by a chain belt 77 with the shaft of roller 36 for driving the conveyer 32. The conveyer 25 31 is driven through the medium of a cross belt 76', Figs. 2 and 11, from a pulley on 76 to countershaft 76 above, thence by sprocket chain 77' to roller 34, while the shaft 71 is driven by means of a chain belt 30 78 from a countershaft 79 in turn geared through the medium of a chain belt 80 with the main drive shaft 50. The belt 80 is arranged for travel upon a suitable sprocket wheel on the shaft 79 and a corresponding 35 sprocket 81 mounted idly on the shaft 50, the last named sprocket being provided with a hub 82 having clutch teeth in normal engagement with corresponding teeth formed on the hub 83 of the fly wheel 54, as seen 40 more clearly in Fig. 10, there being coiled upon the outer end of shaft 50 a compressible spring 84 designed to act upon the sprocket 81 for maintaining the clutch teeth thereon in engagement with the clutch teeth 45 on the hub 83. It will be observed in this connection that during reverse rotation of the shaft 50 in the operation of backing the machine the clutch member 83 may turn independently of the sprocket 81, thereby automatically throwing the reaping mechanism and conveyers out of action.

The movable sickle blade 26 is reciprocated through the medium of a bell crank lever 85 fulcrumed at its elbow as at 86, and 55 having one of its arms engaged with the blade and its other arm connected by means of a link 87 with an eccentric head 88 fixed on the shaft 71 and having a wrist pin 89 engaged with the rear end of the rod 87, it being understood that as the shaft 71 revolves the pitman rod 87 will actuate the bell crank lever, which in turn will reciprocate the sickle blade.

The threshing mechanism, which is housed in the casing 42 includes a thresher cylinder

having teeth 91 adapted to coöperate with teeth 92 fixed in the perforated grain bed 93 above which there is also arranged a plurality of beater cylinders or drums 94 equipped with teeth 95 and adapted to act 70 upon the grain after it passes beyond the action of the thresher cylinder 90, the cylinders 94 being connected for rotation one from another through the medium of an endless sprocket belt 96 arranged for travel 75 around sprocket wheels fixed on the ends of the cylinder shafts and to be driven from the shaft 97 of the engine 47 by means of a belt 98 arranged for travel on a belt wheel 99 fixed on the engine shaft and a belt pulley 100 fixed on the shaft of one of the cylinders while the thresher cylinder 90 is driven from the shaft 97 through the medium of a belt 101 arranged for travel on a belt wheel 102 fixed on the shaft 97 and on a belt pulley 103 fixed on the shaft of cylinder 90, it being understood, of course, that while the engine is in the operation of driving the shaft 97, the thresher cylinder 90 will be driven through the medium of the belt 101 while the beater 90 cylinders 94 will be operated by means of the belt 98 and the sprocket and chain connection 96.

Arranged beneath the grain bed 93 below the thresher cylinder 90 is a downwardly inclined chute 104 while a reversely inclined chute 105 is also arranged beneath the bed under the beating rollers 94. The chutes 104 and 105 are connected for uniform movement by means of a bell crank lever 106 and further sustained for oscillation in the casing by means of links 107, the chutes being adapted to deliver the grain onto the upper end of a downwardly and rearwardly inclined screen 108 having a finely perforated 100 forward portion 109 and a coarsely perforated rear portion 110 beneath which latter there is disposed a downwardly and forwardly inclined pan 111 adapted to direct the material into an underlying conveyer trough 112 containing a tailings conveyer screw 113, the material passing through the portion 109 of the screen being in like manner directed to an underlying conveyer trough 114, containing a conveyer screw 115, by means of a system of underlying inclined pans and screens 116, 117, 118, and 119 and of which the pans 111, 116 and 118 are composed of metal. If desired, there may be arranged in the casing 42 just above the delivery end of the conveyer 38, a beater 144 driven from the shaft 73 by a belt 144.

Mounted on the outer face of the rear side wall of the casing 42 and having communication with the latter is a pair of conveyer ducts 120 and 121, of which the former communicates at its lower end with the conveyer trough 112 and elevates the tailings back to the threshing cylinder 90 through the medium of a spout 122, while the duct 121 com- 125 130

municates at its lower end with the trough 114 which takes the clean grain to the sacker to be cared for.

Fixed on the shaft of the central beater 5 roller 94 is a pulley 131 to which is eccentrically pivoted a pair of pitmen 132 and 133, of which the pitman 132 is connected with a crank arm 132^a in turn fixed on a shaft 132^b carrying the triple crank 196, 10 while the pitman 133 is connected with a crank 133^a fixed on shaft 133^b carrying a crank 134 for oscillating screens 117, 119 and pan 118. The conveyers 113 and 115 and the elevators are driven by convenient 15 pulleys on the projecting shafts through the beaters 94, while disposed for rotation in the thresher casing 42 and to direct a blast of air onto the screens is a fan 141 in turn inclosed within a fan casing 142 and connected to be driven from the right hand beater roller 94 through the medium of a crossed belt 143.

The platform 1, which carries the engines, boiler and attendant parts, is yieldably sustained at its forward end through the medium of vertically compressible supporting springs 146, which by means of interposed boxing rest on the gudgeons 61' and at its rear end by means of similar springs 147 30 which bear at their upper ends beneath members or rails 148 and at their lower ends upon bearing levers 149 in which the rear axle 2 is journaled and which are in turn pivoted at their forward ends as at 150 to 35 the frame of the machine and mounted at their rear ends upon vertical guide members or bolts 151, as seen more clearly in Fig. 6.

The device connecting the bell crank 85 with the sickle is shown clearly in Figs. 14, 40 15 and 16. In Fig. 15 is shown how the plate portion of the bell crank 85 passes through the breast of the reaper platform and extends out under the sickle bar 152 and has the adjustable parts 153 bolted 45 thereon. Fig. 16 shows how the sickle bar 152 having the cutting sections 26 attached may be in two pieces abutting together as at 154, the two sections of the sickle bar being bolted between 155 and 156 as shown, 50 155 having a boss on the lower side which is engaged by the adjustable pieces 153. The pieces 153 are fastened to the plate 85' by means of cap screws 157 passing through slotted holes in 85' and screwed into the 55 pieces 153, and by the taper bolts 158 passing through slotted holes in the pieces 153 and the plate 85'. The slotted holes are shown by the dotted lines in Fig. 16. The pieces 153 engaging the boss on 155 may be 60 adjusted to take up all lost motion or looseness causing jar of the working parts by tightening the tapering bolts 158.

In practice, the engines having been set in motion, the machine will travel over the 65 ground and the reaping, conveying and

threshing devices will be driven through the medium of the various sets of gearing, as heretofore explained. As the machine advances, the sickle blade 26 will cut the grain or other material, which will fall onto the 70 conveyers 31 and 32 from which it is received by the conveyer 38 and delivered thereby into the casing 42 through the opening 41. After entering the casing the grain first passes under and is subjected to the action of the thresher cylinder 90 and thereafter to the action of the beater cylinders 94, whereby the grains will be effectually removed from the sheaths, the straw finally passing into the straw receiving chamber 80 152 at the rear end of the casing 42. The grain falls as usual through the perforated bed 93 onto the chutes 104 and 105 and thence passes to the underlying screens and pans. Upon falling onto the screen 108 the 85 clear grain passes through the portion 109 of said screen onto the underlying system of screens and pans by which it is finally delivered into the trough 114 and carried therefrom by the screw 115 into the conveyer 90 duct 121 for final delivery into grain sacks. The coarser particles of material falling onto the screen 108 pass onto the portion 110 thereof through which it is delivered to the underlying pan 111 and directed by the latter into the trough 112 from which it is conveyed by the screw 113 into the duct 120, thence carried back to the cylinder 90 for rethreshing.

It is to be noted that during forward 100 movement of the machine the clutch members 82 and 83 formed respectively on the sprocket pinion 81 and wheel 54 will be maintained in engagement by the spring 84, but that when it becomes necessary to 105 back the machine in the operations of turning or the like the spring 84 will be compressed, thus permitting the teeth of the clutch member 82 to ride idly over the teeth of the companion clutch member, whereby 110 the mechanism for driving the harvesting and conveying devices will be thrown out of action, it being understood that the threshing mechanism is independently thrown out of action by stopping the engines 47.

It is to be understood that any engine or motor of sufficient power may be placed on the above described platform and connected to the machinery for operating the same.

Having thus described the invention, what 120 I claim is:—

1. The combination of a wheel-supported frame, runners or ground-engaging members extending forwardly therefrom, a reaper frame extending transversely in front of the 125 first-mentioned frame, upwardly-extending members on the runners, rack bars on the members, guides on the reaper frame for receiving the members, pinions engaging the rack bars, and means for actuating the pin- 130

ions for raising or lowering the reaper frame with respect to the runners.

2. In a machine of the class described, the combination of an engine-propelled vehicle, 5 runners pivotally connected with the vehicle and extending forwardly therefrom, a reaper frame, members extending upwardly from and supported on the runners and located behind the reaper frame, means for 10 guiding the frame on the members, a counterbalancing device on the vehicle, means for connecting the device with the frame, and means on the frame operating through the members for raising and lowering the frame 15 with respect to the runners.

3. In a machine of the class described, the combination of a vehicle, runners connected therewith and located at opposite sides of the vehicle, upright members supported on 20 the runners, a reaper frame disposed in front of the members, means on the frame and arranged to operate through the members for raising and lowering the frame, a support on the vehicle, a beam pivotally mounted on 25 the support, a link connected with the front end of the beam and with the reaper frame at the middle thereof, and a counterbalancing weight on the rear end of the beam.

4. The combination of a wheel-supported 30 frame, runners projecting forwardly therefrom and connected therewith, a horizontal reaper frame, upright members on the runners and disposed behind the reaper frame, means on the frame slidably engaging the 35 members, and mechanism for raising and lowering the reaper frame at both ends simultaneously.

5. The combination of a wheel-supported 40 frame, forwardly-extending runners thereon, a reaper frame disposed over the runners, means for supporting the frame on the runners and for vertically adjusting the frame with respect to the latter, endless belts on the 45 reaper frame, an endless elevator upon which the belts discharge, a driving shaft, a second shaft, a cross belt between the shafts, a sprocket and chain connection between one

shaft and one of the belts, and a sprocket and chain connection between the other shaft and remaining belt. 50

6. In a machine of the class described, the combination of a vehicle, a motor for propelling the same, a shaft driven by the motor, a countershaft, a mechanism between the two shafts and including means for preventing the countershaft from rotating when the vehicle is moved rearwardly, a reaper frame, reels mounted thereon, a shaft on the frame, a sprocket and chain device between the shaft and reels, a cross belt between the 60 countershaft and reel-operating shaft, endless feed belts on the frame, sprocket and chain mechanisms for actuating the belts to feed inwardly, driving means between the countershaft and said mechanisms for simultaneously actuating the latter, sickle bar, means for reciprocating the same, a crank on the countershaft, a connection between the crank and the power actuating means, runners extending under the reaper frame 70 and pivotally connected with the vehicle, upright members supported on the runners, and means on the frame and actuated from the vehicle and operating through the members for raising and lowering the frame. 75

7. In a machine of the class described, the combination of a vehicle, a reaper frame, runners connected with the vehicle and projecting under the frame, upright members carried by the runners, fixed guides on the 80 frames through which the members extend, rack bars on the members, a shaft carried by the frame, pinions on the shaft, a second shaft mounted on the frame and on the vehicle, a gearing between the shafts, and means 85 for actuating the second shaft for raising and lowering the reaper frame.

In testimony whereof, I affix my signature in presence of two witnesses.

LEWIS K. BROWN.
